UNITED STATES PATENT OFFICE.

JOHN DEAN, OF RACINE, WISCONSIN.

HAIR CLIPPER.

Application filed October 30, 1923. Serial No. 671,718.

To all whom it may concern:

Be it known that I, JOHN DEAN, a citizen of the United States of America, and resident of Racine, county of Racine, State 5 of Wisconsin, have invented certain new and useful Improvements in and Relating to Hair Clippers, of which the following is a specification.

This invention involves the provision of a 10 sanitary guard forming a peculiar base plate for hair clippers; and the objects and nature of the invention will be readily understood by those skilled in the art in the light of the following explanations of the 15 accompanying drawings that illustrate what I now believe to be the preferred mechanical expression or embodiment of my invention from among other forms, constructions and arrangements within the spirit 20 and scope thereof.

An object of the invention is to provide simple means for covering the under surfaces of the comb or bottom blades or plates of hair clippers to prevent contact thereof with 25 the skin of the person operated on, except where necessary to expose the comb teeth or cutting portions of such blades, and to render such means readily removable and attachable, for cleansing or other purposes; 30 and a further object is to utilize such means to provide hair clippers with a rounded or convexed base or bearing surface on which such clippers can be easily rocked or tilted during the clipping operation to vary the 35 distance between the cutters and skin and hence the length of the hair stubble after the cutting operation.

With these and other objects in view my 40 invention consists in certain novel features of construction or formation, or in combinations and arrangements, as more fully pointed out and specified hereinafter.

Referring to the accompanying drawings:

45 Fig. 1 is a bottom plan showing a hair clipper (partially broken away) equipped with my invention.

Fig. 2 is an end edge elevation of the constructions disclosed by Fig. 1.

50 Fig. 3 is a top plan of the disclosure of Fig. 1.

Fig. 4 is a section on the line 4—4, Fig. 1, but showing the comb blade and guard only on an enlarged scale.

Fig. 5 is a section on the line 5—5, Fig. 55 1, but showing the comb blade and guard only on an enlarged scale.

Fig. 6 is a detail perspective view of the 60 base or face plate and protective guard of my invention.

The hair clipper shown, embodies flat 65 comb or bottom blade or plate 1, and flat top or reciprocating cutter blade or plate 2. The bottom or comb blade 1, is formed at its front edge into the comb cutting teeth 1^a, 65 of the clipper, and the front edge portion of upper blade 2 is formed into cutting teeth 2^a, that cooperate with comb teeth 1^a, in the usual or any other suitable manner to cut or clip hair. The comb blade 70 1, is flat at its under surface, except for the front edge bevel 1^b that forms the comb teeth 1^a, with an upward and forward bottom edge taper, and except for the fore and aft ridges or corrugations 1^c, in longitudinal 75 rearward extension of the lower edges of teeth 1^a, respectively.

The comb or bottom blade 1 is secured as 80 by screws (not shown) to, and is arranged below, the main supporting body or frame 4, from which the rigid handle 5 projects. The swingable spring pressed operating handle 6, is pivotally mounted to or on the body 4 and is operatively coupled to the upper or reciprocating cutter blade, to actuate 85 the same.

The comb blade 1, intermediate its front 90 and rear edges, is formed with a top groove 1^d that extends through both end edges of said blade.

Holes for the screws that secure the comb 95 blade and for other screws securing certain lugs on the top face of the comb blade, extend through the under surface of said blade, in the usual type of hair clipper.

The hair clipper shown, and as thus far described, is well known to commerce and to those skilled in the art. These clippers now in common use are objectionable from the sanitary standpoint, in that the bottom surfaces of the comb blades come in direct contact with the moist skin with a resulting action on the exposed surfaces of the comb blades that tends to roughen the same by corrosion, rust or otherwise. The bottom surfaces of the blades thus tend to carry infection particularly as the roughening thereof prevents proper wiping and cleansing of 100 105

such surfaces. It is difficult if not impossible to sterilize a hair clipper after each hair cutting operation, even should it be possible to so treat a hair clipper without injury thereto. The screw heads and ends that are exposed at the bottom face of the comb blade, also tend to present objectionable sharp edges as well as leave crevices for the collection of filth and germs. Also, the flat bottom surface of the comb blade renders it difficult to feather off the hair, by tilting the clipper on the skin to vary the distance between the skin and the cutting points, as will be well understood by those skilled in the art.

I have successfully solved the problem of overcoming these difficulties by the provision of a peculiar sanitary guard, face or base plate, which in the particular embodiment illustrated as an example for purposes of explanation, is struck or pressed up in one piece from thin elastic or spring non-rusting non-corrodable sheet metal or of other thin spring sheet metal such as brass or other metal, coated or plated with nickel or other suitable metal to provide smooth non-rusting non-corrodable exposed surfaces. This guard is designed to cover the rear or heel edge of the comb blade of the clippers, the major portions of the lengths of the end edges of said blade, and the entire bottom surface of the blade up to the bases of the comb teeth, i. e., up to the bevel of the front end of the comb blade, and the bottom or body of this guard is arched, convexed or rounded downwardly from its front edge to its rear edge to provide a bearing surface on which the hair clipper can rock and slide to elevate the cutting teeth to the desired elevation from the skin and maintain them at such elevation during the hair cutting operation.

This thin spring sheet metal guard forms the bottom plate or body 10 of dimensions 45 to entirely cover the comb blade at least up to the front bevel thereof, and this body 10 is formed with the upstanding flange 11 which is continuous around the body plate 10 from one end of the front edge 12 of 50 said body plate to the opposite end of said front edge. The guard is thus open or non-flanged at its front end and the front edge 12 is straight. The upstanding flange 11 is designed to extend upwardly at the exterior 55 of and cover the otherwise exposed rear and end edges of the comb blade and to maintain the guard properly positioned on said blade against relative forward and endwise movement. In this example, the flange covers the 60 blade ends except for the upwardly beveled front ends thereof. The end portions of the flange are formed with upwardly projecting inwardly deflected or indented spring retaining projections, tits or fingers 13, designed 65 to snap over the top faces of the end por-

tions of the blade to detachably retain the guard in proper position on the blade.

These spring fingers 13, in the example shown, are arranged to snap into the depressions in the blade ends formed by the top groove 1°, and lap over the floor of said groove and thus normally hold the guard tightly up against the bottom of the blade and against sliding rearwardly from the blade.

The guard is so formed as to be readily removed from the blade for sterilization or other cleansing after each hair cutting operation, and to be readily fitted and snapped back into operation position on the blade.

The body plate of the guard is formed with parallel closely arranged ridges or corrugations 10^a from front to rear to correspond with and at the front edge of the guard fit into or intermesh with the approximately similar ridges or corrugations on the bottom face of the blade. The body plate of the guard is concavo-convex from front to rear to form the downwardly arched or convexed bearing surface and consequently the top face of the body plate of the guard fits or engages the under face of the comb blade only at the rear edge portion thereof and the beveled front edge portion thereof. The front straight edge portion of the body plate of the guard is inclined upwardly and forwardly and laps over onto and fits the beveled front edge portion of the comb plate approximately in the direction and at the angle of the bevel so as to form an approximately smooth joint therewith and rearward continuation at approximately the same angle as the bevel.

Those skilled in the art will appreciate the utility and advantages of this guard without necessity of further detail explanation.

It is evident that various changes, departures, and modifications might be resorted to in the forms and constructions described without departing from the spirit and scope of my invention, and hence I do not wish to limit myself to the exact disclosure hereof.

What I claim is:

1. A sanitary guard for the comb blade of a hair clipper, struck up from thin spring sheet metal providing a body plate convexed from its front to its rear edge, to cover the bottom face of the comb blade rearwardly from the front edge bevel thereof and having an upstanding flange 11 to fit the end and rear edges of the blade.

2. A sanitary guard for the comb plate of a hair clipper formed to cover the bottom face of the blade from the front edge portion thereof rearwardly, and having means for removably attaching the guard to the clipper and having front to rear corrugations or ridges coinciding at the front edge 130

of the guard with the corresponding corrugations or ridges on the under side of the comb blade.

3. A sanitary guard formed to cover the bottom face of the comb blade of a hair clipper from the beveled front edge portion of the blade rearwardly and having an upstanding flange extending around the guard from one end of its front edge to the other 10 end of its front edge, said guard formed with means for detachably clamping the guard to the comb blade.

4. A hair clipper sanitary guard having upstanding end spring fingers to snap into 15 top depressions in the comb blade of the hair clipper, said guard forming a face plate covering the bottom face of the comb blade from its front bevel rearwardly and arched downwardly from its front edge to its heel,

the front edge portion of said guard inclined 20 upwardly and forwardly and formed at its front edge to snugly fit the upwardly and forwardly beveled front edge portion of the blade.

5. A sanitary guard to approximately entirely cover and removably fit the comb blade of a hair clipper, said guard having a flange to overlap the end and rear edges of the blade, and being arched or convexed downwardly from its front edge to its heel to 30 provide the hair clipper with a rounded bottom bearing surface on which the hair clipper can be rocked to raise and lower its cutting teeth with respect to the surface of the skin.

Signed at Racine, Wisconsin, this fifth day of October, 1923.

JOHN DEAN.
